UNITED STATES PATENT OFFICE

165,407

TOY RATTLE

Harry B. Toombs, New York, and George
Amberge, Mount Vernon, N. Y.

Application September 6, 1950, Serial No. 12,074

Term of patent 14 years

(Cl. D34—15)

To all whom it may concern:

Be it known that Harry B. Toombs and George Amberge, both citizens of the United States, residing, respectively, in the city of New York, county of New York, State of New York, and the city of Mount Vernon, county of Westchester, State of New York, have invented a new, original, and ornamental Design for a Toy Rattle, of which the following is a specification, reference being had to the accompanying drawings, forming a part hereof, wherein:

Fig. 1 is a front elevation of the toy rattle showing our new design; and

Fig. 2 is a side elevation thereof.

We claim:

The ornamental design for a toy rattle, substantially as shown.

HARRY B. TOOMBS.
GEORGE AMBERGE.
